UNITED STATES PATENT OFFICE.

EDWARD F. SEBESTA, OF MINNEAPOLIS, MINNESOTA.

AUTOMOBILE SIGNAL.

Application filed June 16, 1926. Serial No. 116,420.

This invention relates to new and useful improvements in signals, and particularly to direction signals for automobiles.

One object of the invention is to provide a device of this character wherein a single operating means is capable of moving a signal member or arm into and out of signaling position to indicate one or the other of two directions.

Another object is to provide a device of this character wherein the operating means for the signal arm is adapted to be turned, to a certain degree, in each direction to accomplish the raising and lowering of the arm, and further rotation in either direction to cause the arm to rotate simultaneously with its swinging movement.

Other objects and advantages will be apparent from the following description when taken in connection with the accompanying drawings.

In the drawings:

Figure 1 is an elevation of the device, the signal being in raised position, in full lines, and in lowered position, in dotted lines, the casing being broken away.

Figure 2 is an enlarged vertical sectional view on the line 2—2 of Figure 1.

Figure 3 is an enlarged vertical transverse sectional view on the line 3—3 of Figure 1.

Figure 4 is a longitudinal sectional view on the line 4—4 of Figure 1.

Figure 5 is a section on the line 5—5 of Figure 4.

Figure 6 is a section on the line 6—6 of Figure 4.

Figure 7 is an elevation of the signal arm.

Figure 8 is a transverse section, on the line 8—8 of Figure 1.

Referring particularly to the accompanying drawings, 10 represents an elongated casing which is provided with the means 11 for attaching same to the front of an automobile, at the driver's side, so that said casing will project horizontally from the side of the automobile. On the outer end of the casing 10 there is formed a cylindrical casing 10', having the front and rear brackets 12 in which is rotatably supported the shaft 13. Disposed horizontally through the inner end portion of the casing 10 is a shaft 14, which projects rearwardly toward the driver, and is provided with a handle 15 by means of which the shaft may be rotated. Fixed on this shaft, within the

casing, is a radially extending arm 16, to which is pivotally connected one end of a rod 17, said rod extending longitudinally of the casing and being pivotally connected to a second arm 18, associated with the shaft 13. Extending vertically from the lower wall of the casing 10, adjacent the inner end thereof, is an apertured bracket 19, while a similar bracket 20 depends from the upper wall, adjacent the outer end of the casing. Rotatably supported in these brackets 19 and 20, and extending longitudinally within the casing, is a rock shaft 21. On the outer end of the rock shaft 21 is fixed a radial arm 22, which is pivotally connected with a slideable plate 22' carried by the front bracket 12, said plate being provided with a projecting stop block 23, to which reference will be made later herein. Fixed on the rock shaft 21, adjacent its inner end, is a bifurcated arm 24 which straddles the before-mentioned rod 17, and is adapted to be moved from side to side, to cause the said shaft to rock, as the rod operates.

Secured to the shaft 13, by means of the arm 18, are the arms of a yoke 25, and secured to the intermediate portion of said yoke is a hub member 26, which is formed with an elongated arm 27, turned angularly at its outer end, as at 28, to receive a bolt 29. Disposed through the hub, and through the said intermediate portion of the yoke, is a shaft 30, having on one end a bevel gear 31 which is disposed between and meshes with the two bevel gears 32 and 33, loosely mounted on the shaft 13. On the end of the shaft 30, remote from the gear 31, is a radial arm 34, which has its outer end secured to the end plate 35, of the signal casing 36. This plate 35 has a central opening 37 through which the hub 26 is loosely disposed. The before-mentioned bolt 29 is secured in the other end plate 35' of the signal casing 36, and clamps the glass side plates 38 said plate and the plate 35. Formed integrally with the gears 32 and 33 are the collars 39 and 40, respectively, which have the radially extending lugs 41 and 42, disposed at different circular angles around the shaft 13, for engagement with the before-mentioned stop block 23. It will be noted that the gear 31 is in constant mesh with the gears 32 and 33.

Assuming the signal casing to be in vertical position, so that the glass panels containing the legend Right are directed for-

wardly and rearwardly, respectively, the driver grasps the handle 15 and rotates the shaft 14 toward the right, which exerts a pull on the rod 17 and causes the rocking of the yoke, and the downward swinging movement of the signal casing into horizontal extended position, at the side of the automobile, within full view of drivers approaching from the front or from the rear. 5 A rotation of the shaft 14 toward the left swings the casing back into its vertical, non-signaling position. Upon continued rotation of the shaft 14 toward the left the rod 17 swings the bifurcated arm 24 whereby 10 to rock the shaft 21, to slide the plate 22' downwardly until the stop block 23 is in the path of the lug of the gear 33. The gear 33 is thus held against rotation, and upon further turning of the shaft 14, in the direction 15 above mentioned, the rod 17 swings the signal arm toward lowered signaling position, whereby the gear 31 will roll around on the gear 33, with the result that the signal arm is rotated to display the legend Left to view, 20 from both the front and rear of the automobile. Turning the shaft 14 to the right swings the signal arm into vertical position again, without rotation by the gears, as said 25 gears 32 and 33 are loose on the shaft 13. 30 Then, upon further turning the shaft 14, toward the right, the rod 17 will rock the shaft 21 to shift the plate 22' upwardly to dispose the stop block in the path of the end 35 of the gear 32, with the result that the gear 31 will roll on this gear 32, as the shaft 14 is turned to swing the signal arm downwardly, so that said signal arm will be rotated to display the legend Right. 35

By this construction, the operator can 40 swing the signal member from vertical to horizontal position, and back again, without rotation of the signal member, or he can cause the rotation of said member, in either direction, by simply continuing the rotation of the shaft 14 in the direction corresponding to the legend to be displayed. 45

What is claimed is:

1. A signaling device comprising a signal arm capable of swinging in a vertical plane and axial rotative movements, and an operating means connected with the signal arm and movable in one direction to simultaneously rotate the arm, and to swing the arm from vertical to horizontal position, and movable 55 in the other direction to swing the arm into a vertical position.

2. A signaling device comprising a signal arm capable of swinging movement in a vertical plane and axial rotative movement, 60 and a rotatable operating means the movement of which in one direction produces a rotative movement of the signal arm, simul-

taneously with a swinging movement of said signal arm from vertical to horizontal position, and movement of the operating means 65 in the opposite direction produces a swinging movement of the arm from horizontal to vertical position.

3. A signaling device comprising a signal arm capable of swinging movement in a 70 vertical plane and axial rotative movement, and a rotatable operating means connected with the signal arm, said operating means being adapted to be moved in one direction to produce a rotative movement of the arm 75 simultaneously with a swinging movement of the arm from vertical position to horizontal position, and to be moved in the opposite direction to produce a swinging movement of the arm from horizontal 80 position to vertical position.

4. A signaling device comprising a signal arm capable of swinging movement in a vertical plane and axial rotatable movement, and means operatively connected with the 85 arm and operable in one direction to swing the arm from vertical position, to horizontal position, and to rotate the arm during such swinging movement, said operative means being adapted to be then operated in the 90 opposite direction to restore the arm to vertical position.

5. A signaling device comprising a signal arm capable of vertical swinging movements and axially rotative movements, said arm being mounted on an axis, means on the axis for rotating the arm, means for selectively holding one of the axis carried rotating means against rotation, and an operating means connected with the axis and with the 100 selecting means for actuating the latter upon initial movement, and for turning the axis and swinging the arm upon final movement in the same direction, said operating means being arranged to be moved in the opposite 105 direction whereby to restore the arm to normal position without actuation of the selecting means.

6. A signaling device comprising an axis, 110 gears loosely mounted on the axis and each having a projection, a signal arm including a shaft having a gear in simultaneous engagement with said loose gears, a block selectively movable into the paths of said projections whereby to hold the engaged gear 115 against rotation, an operating shaft, a link connected with the shaft and with the signal arm, and means connected with the said block and movable by the said link whereby to selectively dispose the block in the paths 120 of said gear projections.

In testimony whereof, I affix my signature.

EDWARD F. SEBESTA.
